UNITED STATES PATENT OFFICE.

WALTER E. HOLLAND, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

DESIGN FOR A BATTERY VENT CAP.

Application filed February 27, 1923. Serial No. 5,299. Term of patent 14 years.

To all whom it may concern:

Be it known that I, WALTER E. HOLLAND, a citizen of the United States, residing in Philadelphia, Pennsylvania, have invented a certain new, original, and ornamental Design for a Battery Vent Cap, of which the following is a specification, reference being had to the accompanying drawings, forming part thereof, in which:

The figure is a perspective view of the battery vent cap forming the subject of my new, original and ornamental design.

I claim:

The ornamental design for a battery vent cap, substantially as shown.

WALTER E. HOLLAND.
